Patented June 1, 1920.

FIG. 1

FIG. 3

INVENTOR
J. W. GRIFFITH

BY *Franklin*

ATTY.

UNITED STATES PATENT OFFICE.

JOHN W. GRIFFITH, OF SAN FRANCISCO, CALIFORNIA.

WRITING-POSITION PENHOLDER.

1,341,847.

Specification of Letters Patent. Patented June 1, 1920.

Application filed February 2, 1920. Serial No. 355,680.

To all whom it may concern:

Be it known that I, JOHN W. GRIFFITH, a citizen of the United States, residing at San Francisco, in the county of San Francisco and State of California, have invented new and useful Improvements in Writing-Position Penholders, of which the following is a specification.

This invention relates to a device the use of which will insure the holding of a pen holder and the fingers in the correct writing position and require the "forearm" or "muscular" movement, which is acquired ordinarily with much difficulty. The device is in the form of an attachment for pen holders and capable of adjustment to fit the fingers and hand of the particular writer.

Teachers of penmanship experience much difficulty in having the pupils maintain the pen holder in proper position and it is also difficult for the pupils to maintain this position. I therefore provide a simple and inexpensive device which when attached to a pen holder will act as a guide for the pupil or writer and not necessitate clasping the pen with the fingers, and which will hold the pen and hand in the proper and correct position to secure the best results in writing. The device is so constructed that cramping of the fingers and hand is avoided and the free "forearm" or "muscular" movement must be resorted to in writing.

The invention possesses other advantages and features, some of which, with the foregoing will be set forth at length in the following description, where I shall outline in full, that form of the invention which I have selected for illustration in the drawings accompanying and forming a part of the present specification. In said drawings I have shown one form of the construction of my invention but it is to be understood that I do not limit myself to such form, since the invention as expressed in the claims may be embodied in a plurality of forms.

Referring to the drawing:

Figure 1 is a perspective view showing the invention as it would appear when in use, Fig. 2 is a similar perspective view of the invention from another point of view and Fig. 3 is a top plan view of the device attached to a fragment of a pen holder.

Referring to the present embodiment of the invention illustrated in the accompanying drawing, 1 designates a pen holder of the ordinary type, 2 the pen point in said

holder, and 3 the correct position attachment of my invention.

The device of my invention comprises essentially guide portions which, when the pen holder or a pencil, or other writing instrument, is clasped by the writer, will insure the proper holding of the pen holder or instrument and the correct disposition of the fingers relative to the holder. To this end, there is provided an attachment sleeve 4 which is preferably cylindrical and split in order that it may be slipped over and clamped upon the pen holder as shown in Fig. 3 of the drawings. On one side of this sleeve 4 there is provided a thumb rest 5 which is preferably concave on the side thereof engaged by the thumb as shown in Fig. 2 of the drawings.

On the other side of said sleeve there is carried a first and second finger guide device which comprises a relatively straight arm 6 adapted to extend upwardly from the sleeve 4 along the pen holder 1. Carried by this arm 6, on opposite sides, are pairs of arched keepers 7 and 8, each pair being arranged adjacent to the extremities of said arm whereby the fingers may be extended under and engaged by these keepers on opposite sides of the second knuckles of the fingers as shown in Fig. 2. Extending outwardly from the inner end of the arm 6 substantially at right angles to said arm and pen holder is a loop 9 having a downwardly extending portion 10 for engagement at its lower end with the paper being written upon. The lower end of the member 10 may be enlarged and rounded as at 11, so that it will move freely over the paper. The front side 12 of the loop 9 is comparatively straight 95 whereas the rear side is curved as at 13. The third and little fingers are inserted through this loop so that the backs of said fingers will rest against the straight side 12 of the loop and be disposed in said position 100 to have the finger nails rest lightly upon the paper being written upon. A supporting member 14 is fixed to the sleeve 4 substantially in line with the keepers 8 so as to support the tip of the second finger, the tip 105 of the first finger being supported upon the top of the pen holder as is ordinarily the case in clasping a pen. The arm 6, loop 9, and member 14 are joined and preferably the entire device is formed of one piece of 110 spring wire. The keepers 7 and loop 9 may be bent into proper shape to fit the fingers of

the particular person using the device. The wire where the arm 6 and loop 9 are connected with the member 14 is preferably twisted as at 15 to provide a spring hinge 5 connection between the arm 6 and loop 9. Thus when the device is fitted upon a pen holder the tendency of the spring hinge normally holds the device with the arm 6 extending slightly to the left side of the pen 10 holder and when the fingers are properly inserted in the device the spring action tends to hold the device securely in place against the fingers.

In use, the writer places the pen holder 15 in the hollow between the thumb and first finger, inserts the first and second fingers under the keepers 7 and 8 and places the third and little fingers within the loop 9. The loop 9 is arranged relative to the keepers 20 7 and 8 so that the third and little fingers must be crooked or bent in order to be inserted and the finger nails will therefore rest upon the paper as shown in Fig. 1. The second finger tip rests upon the member 14 25 and the thumb engages the thumb piece 5. With the pen thus held as shown in Figs. 2 and 3, the writer is required to maintain the correct writing position and the fingers and hand are not cramped in any way and 30 permitted freedom of movement sufficient to provide accuracy in writing. The member 10 on the outer end of the loop 9 supports the hand on the right side of the pen holder so that when the hand is pressed down- 35 wardly the majority of the pressure will be taken up in the loop 9 and member 10. The sleeve 4 may be moved up and down on the pen holder until the proper position to best suit the particular writer is obtained.

40 It will be seen that I have provided a device which is not only an aid to writers, but will be a boon to teachers and instructors of penmanship in that by its use the pupil is required to hold the pen in correct writing 45 position and maintain said position throughout the operation of writing. The device will be of great use in teaching children in that after a short continued use of the device the hand and fingers will be trained to 50 hold the pen in proper writing position.

To assume the proper writing position, and secure best results with the device, the right arm should be placed on the desk or support, the writer resting on the muscles 55 just forward of the elbow, with the nails of the third and little fingers resting on the paper and the wrist clear of the paper. In

this position, the hand, fingers, and pen should be moved as one when writing and a smooth even stroke will be made. 60

It is to be understood that wherever the word "pen holder" is used or the word "pen" in the sense of pen holder, a pencil may be substituted, as the device is equally applicable for writing with a pencil as for writing 65 with a pen.

I claim:—

1. In combination with a pen holder having a pen point at one end and of a sleeve receiving said pen holder, a finger receiving 70 loop secured to said sleeve and extending outwardly to one side of the pen holder, a downwardly extending member on the outer end of said loop for engagement with the paper being written upon, a thumb piece on 75 said sleeve and finger guides fixed to said sleeve.

2. In combination with a pen holder, a sleeve mounted upon said pen holder, a finger receiving loop extending outwardly 80 from said sleeve, a downward extension on said loop adapted to engage the paper being written upon, an arm secured to said sleeve finger keepers supported by and extending on opposite sides of said arm for reception 85 of the first and second fingers of the hand and a thumb piece carried by said sleeve.

3. In combination with a pen holder, a sleeve mounted upon said pen holder, a finger receiving loop extending outwardly 90 from said sleeve, a downward extension on said loop adapted to engage the paper being written upon, an arm secured to said sleeve finger keepers supported by and extending on opposite sides of said arm for reception 95 of the first and second fingers of the hand, and a thumb piece carried by said sleeve, and a member for supporting the tip of the second finger carried by said sleeve.

4. In combination with a pen holder, a 100 sleeve mounted upon said pen holder, a finger receiving loop extending outwardly from said sleeve, a downward extension on said loop adapted to engage the paper being written upon, an arm secured to said 105 sleeve and extending in the direction of the length of said pen holder, spaced arched finger keepers extending on opposite sides of said arm for reception of the first and second fingers of the hand and a thumb piece carried by said sleeve, said loop arm and keepers being formed of spring wire. 110

JOHN W. GRIFFITH.
